BALL-DISPENSING ATTACHMENT FOR
POOL TABLES

Douglas F. Price, Crystal Springs, Miss.

Application August 16, 1949, Serial No. 110,485

6 Claims. (Cl. 312—49)

1

This invention relates to billiard ball-dispensing devices, and more particularly to an attachment for a pool table to allow a player to serve himself with billiard balls by the insertion of a coin and to allow the player to secure scratched balls when the cue ball scratches during play.

A main object of the invention is to provide a novel and improved coin-operated attachment for billiard tables to allow a billiard player to serve himself with billiard balls, said attachment being simple in construction, easy to install, and being adjustable to enable any number of scratched balls to be served for a given coin inserted in the attachment.

A further object of the invention is to provide an improved coin-operated billiard ball-serving attachment for billiard tables, said attachment being relatively inexpensive to manufacture, being substantially automatic in operation, and eliminating the need of providing a supervisory attendant to supervise the serving of billiard balls to the tables of a billiard establishment.

Further objects and advantages of the invention will become apparent from the following description and claims, and from the accompanying drawings, wherein:

Figure 1 is a top plan view of a billiard ball-dispensing attachment constructed in accordance with the present invention;

Figure 2 is an enlarged fragmentary detail view in top plan of the billiard ball-metering mechanism employed in the attachment of Figure 1;

Figure 3 is a longitudinal vertical cross-sectional view taken on line 3—3 of Figure 1;

Figure 4 is a longitudinal cross-sectional view taken on line 4—4 of Figure 1;

Figure 5 is a fragmentary enlarged side elevational view, partly broken away, of the metering mechanism disclosed in Figure 2;

Figure 6 is a vertical transverse cross-sectional view taken on line 6—6 of Figure 1;

Figure 7 is an elevational detail view of the metering mechanism shown in Figures 2 and 5, said view being taken on line 7—7 of Figure 2.

Referring to the drawings, 20 designates a rectangular housing adapted to be secured in any suitable manner beneath the forward marginal portion of a conventional billiard table with the lower left corner of the housing, as viewed in Figure 1, disposed below and in communication with the ball-return chute of the table. The housing 20 is provided with a longitudinal partition wall 21 defining a longitudinal space 22 through which the billiard balls

2

dropping from the ball-return chute may pass. Designated at 13 is a short, downwardly and forwardly-inclined plate member secured in the upper rear portion of the space 22. Designated at 12 is an elongated plate member, extending longitudinally in the space 22, and being transversely pivoted at its intermediate portion, as shown at 23, to the side walls of said space for rocking movement therein. As shown in Figure 3, one end of plate member 12 terminates just short of plate member 13 and the other end of plate member 12 terminates a short distance from the forward end wall of housing 20, indicated at 24. Designated at 8 is a longitudinal bar member which is pivoted to partition wall 21 at 25 and which extends through a vertical slot 26 formed in forward end wall 24. Overlying bar member 8 is a transverse pin member 9 which extends through an arcuate slot 27 in wall 21 and is secured by a bracket 28 to the under side of plate member 12 at a location spaced forwardly with respect to the pivotal connection 23 of said plate member. Bar member 8 is provided with a handle 29. By raising the handle 29, the plate member 12 is rotated counterclockwise, as viewed in Figure 3, from its normal full line position to its dotted line position.

Secured in the rear end of space 22 below plate member 13 is a downwardly and forwardly-inclined plate member 14. Designated at 15 is an elongated, downwardly and forwardly-inclined plate member secured in the lower portion of space 22 and extending from beneath plate member 14 to the forward end wall 24. The bottom of the housing 20 is formed with a chute opening 30, and the partition wall 21 is formed with an opening 31 adjacent end wall 24 establishing communication between the forward end of space 22 and the chute opening 30. From Figure 3, it is apparent that with handle 29 in its full line position, the billiard balls entering space 22 will roll off member 13 onto member 12 and roll down member 12 to the right, as viewed in Figure 3, the member 12 being biased clockwise, as viewed in Figure 3, by a spring 32 connecting its forward end portion to the member 15, as shown in Figure 6. When handle 29 is raised to its dotted line position in Figure 3, the member 12 is swung counterclockwise to its dotted line position and the balls thereon roll back to the rear end of member 12 with the last ball thereon resting in the recess between upper ball stop plate 13 and lower ball stop plate 14, as shown in dotted view at 33. When handle 29 is released, spring 32 causes

member 12 to swing clockwise to its full line position in Figure 3, and the ball 33 is released and rolls down member 14 and member 15 and out through the openings 31 and 30 to a suitable tray below the device where the ball is made available for re-play.

Designated at 7 is a vertical grooved bracket member secured to wall 21 outwardly of space 22, and vertically slidable in said bracket member is a ratchet bar 6. Transversely secured to bar 6 are guide pins 34 which extend into vertical slots 35 formed in bracket member 7, constraining the ratchet bar 6 to vertical movement in the bracket member 7. Upward movement of the ratchet bar is limited by the abutment of the upper pin 34 with the upper extremities of the slots 35. Pivottally secured at 36 to lever 8 is a dog 4 which engages the teeth of ratchet bar 6, and is biased clockwise, as shown in Figure 4, by a spring 37 connecting the lower end of the dog to a portion of wall 21 located forwardly of the pivot connection 36, whereby spring 37 urges the upper end of the dog into engagement with said teeth.

The lever 8 extends through a suitable vertical slot 38 formed in bracket member 7.

It will be seen that the number of balls dispensed by the successive lifting of knob 29 will be determined by the allowable upward travel of ratchet bar 6. Each time lever 8 is lifted, the ratchet bar 6 moves upwardly. Designated at 16 is a bracket bar secured at its lower end to wall 21 and having a transverse shaft element 39 rotatably mounted in its upper end. Said shaft element is formed at one end with an upwardly-extending arm 40 connected by a spring 41 to the upper portion of bracket 7. Shaft element 39 carries a dog 5 biased into engagement with the teeth of ratchet bar 6 by the action of spring 41. As shown in Figure 5, the dog 5 is located immediately subadjacent the dog 4.

Shaft 39 is formed with a downwardly and forwardly-extending arm 42 terminating in a transversely-extending portion 3.

Each time ratchet bar 6 is lifted by ratchet dog 4, the bar 6 is maintained in lifted position by the engagement of dog 5 therewith, the dog 5 engaging the tooth of the ratchet bar 6 below that engaged by ratchet dog 4, as shown in Figure 5.

The above described mechanism including ratchet bar 6, ratchet dog 4 and dog 5, constitutes a latching means actuatable step by step to latching position upon rocking movement of the lever 8, the latching means locking the lever 8 after a predetermined number of oscillations thereof.

The forward end portion of wall 21 is formed with a ball release opening 43 which communicates with the discharge chute leading to the opening 30. Slidably mounted in brackets 11, 11 secured to wall 21 is a bar 10 carrying a transverse rod 2 extending slidably through a slot 44 formed in wall 21. The bar 10 is biased forwardly by a spring 45 connecting rod 2 to a point on wall 21 located forwardly of said rod. The forward end of bar 10 normally extends over the opening 43 preventing discharge of the balls carried on member 12 through opening 43 during play.

Designated at 46 is a coin box secured in housing 20 adjacent forward wall 24. Designated at 47 is a coin-receiving chute secured to forward wall 24 and communicating with coin box 46, the chute 47 having a coin slide member 48 slidably mounted therein, the slide member 48 having the conventional apertured external portion 49 located in front of the housing 20. Secured to the

inner end of coin slide member 48 is a bar 1. Bar 1 is formed with an upper depending vertical portion, an offset 50, and a lower vertical portion 51. The upper vertical portion of bar 1 is engageable with the transverse rod 2 when the coin slide member 48 is pushed inwardly, and at the same time, the lower vertical portion 51 is engageable with the transversely-extending portion 3 of shaft element 39.

10 The ratchet bar 6 may be preset, by properly locating the upper pin 34, to allow the ratchet bar to be raised through a distance corresponding to a predetermined number of notches. When said upper pin 34 reaches the top extremities of the slots 35, further upward movement of the ratchet bar 6 is prevented. Said ratchet bar is locked in raised position by the locking dog 5 and the lever 8 is locked in the lowered position of handle 29 by the engagement of dog 4 with the locked ratchet

15 bar.

When a new game is started, a coin is placed in the apertured portion 49 of coin slide 48 and the slide is pushed in. The upper vertical portion of arm 1 engages rod 2 moving release bar 10 rearwardly and causing all the balls on member 12 to be discharged into the ball-release chute through the opening 43 and into the tray below opening 30. At the same time, the lower vertical portion 51 of arm 1 engages transverse arm 3 and rotates shaft element 39 counterclockwise, as viewed in Figure 5, moving dog 5 away from ratchet bar 6. Dog 5 moves dog 4 away from said ratchet bar, thereby releasing the ratchet bar and allowing the bar to drop to its lowered position to start the new game. During the course of the game the player may serve himself with balls by successively raising handle 29 until ratchet bar 6 reaches its upper limiting position, at which time handle 8 becomes locked, as above described, and no more balls may be served until the ratchet bar is unlocked by inserting a coin in the coin slot and pushing the coin slide inwardly.

20 A triangular stop block 52 is secured on the forward corner of member 12 opposite the opening 43 which directs the balls through said opening when the stop bar 10 is retracted. Normally, there is insufficient space between said stop block and the end of stop bar 10 to allow a ball to pass therebetween. A similar triangular directing block 53 is secured to the forward corner of member 15 opposite the opening 31.

25 Although a specific embodiment of a coin-operated billiard ball-dispensing device has been disclosed in the foregoing description, it will be understood that various modifications within the spirit of the invention may occur to those skilled in the art. Therefore, it is intended that no limitations be placed on the invention except as defined by the scope of the appended claims.

30 What is claimed is:

35 1. A billiard ball-dispensing device comprising a housing, means defining a longitudinal chute compartment in said housing, an elongated trough plate extending through the major portion of said compartment, means pivotally mounting said trough plate in said compartment for swinging movement around a transverse axis at the intermediate portion of said trough plate, a longitudinal lever pivoted in said housing, means carried by said lever underlying the forward portion of said trough plate, means biasing the forward portion of the trough plate downwardly, a vertically-moving ratchet bar slidably carried in said housing, releasable pawl means engaging said ratchet bar and arranged

to normally prevent downward movement of the ratchet bar, and a dog carried by said lever and engaging said ratchet bar, said dog being arranged to elevate the ratchet bar responsive to upward movement of the lever.

2. A billiard ball-dispensing device comprising a housing, means defining a longitudinal chute compartment in said housing, a tiltable dispensing trough in said compartment, means for tilting said trough, said last-named means comprising a lever pivoted in said housing and engaging said trough, said lever being arranged to tilt said trough each time the lever is oscillated, means locking said lever after a predetermined number of oscillations thereof, and coin-controlled means for releasing said locking means.

3. A billiard ball-dispensing device comprising a housing, means defining a longitudinal chute compartment in said housing, there being a ball release opening in said compartment, a tiltable dispensing trough in said compartment, means for tilting said trough, said last-named means comprising a lever pivoted in said housing and engaging said trough, said lever being arranged to tilt said trough each time the lever is oscillated, a vertically-movable ratchet bar slidably carried in said housing, a dog carried by said lever for engaging said ratchet bar and arranged to lift the bar each time the lever is lifted, a locking pawl engaging said ratchet bar and arranged to support the bar in elevated position, said locking pawl being pivoted to the housing, means limiting upward movement of the ratchet bar, a movable closure member carried by the housing and normally extending across said opening, means biasing said closure member to a closing position, a coin-controlled slide member, and means on said slide member simultaneously engageable with said closure member and locking pawl to move said closure member to non-interfering position with respect to said opening, the locking pawl being arranged to move the dog away from the ratchet bar responsive to similar movement of the locking pawl.

4. A billiard ball-dispensing device comprising a housing, means defining a longitudinal chute compartment in said housing, said compartment being formed with a ball release opening, a tiltable dispensing trough in said compartment, movable closure means in said compartment normally extending across said opening, means for tilting said trough, means locking said tilting means after a predetermined number of strokes

thereof, and means for simultaneously releasing said tilting means and moving said closure means to non-interfering position with respect to said opening.

5. A billiard ball dispensing device comprising a housing, means defining a longitudinal chute compartment in said housing, a trough plate positioned longitudinally of and within said compartment and mounted intermediate its ends for tilting up and down movement about an axis transverse of said compartment, a lever positioned longitudinally of and within said compartment and mounted in said compartment for rocking movement about a second axis transverse of said compartment, means connecting said lever to said trough plate, means operatively connected to said trough plate adjacent one end for biasing the latter end toward its tilting down movement position, and latching means actuatable step by step to latching position operable upon rocking movement of said lever, said latching means locking said lever after a predetermined number of oscillations thereof.

6. A billiard ball dispensing device comprising a housing, means defining a longitudinal chute compartment in said housing, a trough plate positioned longitudinally of and within said compartment and mounted intermediate its ends for tilting up and down movement about an axis transverse of said compartment, a lever positioned longitudinally of and within said compartment for rocking movement about a second axis transverse of said compartment, means connecting said lever to said trough plate, means operatively connected to said trough plate adjacent one end for biasing the latter end toward its tilting down movement position, latching means actuatable step by step to latching position operable by the rocking movement of said lever, said latching means locking said latching means after a predetermined number of oscillations thereof, and coin controlled means for releasing said locking means.
